FILTER FOR SWIMMING POOL

Salvatore E. Barrera, Mountaintop, Pa., assignor to Muskin Manufacturing Company, Inc., Wilkes-Barre,
Pa., a corporation of Pennsylvania.

Filed Mar. 31, 1966, Ser. No. 1,721

Term of patent 14 years

(Cl. D91—1)

I claim:

The ornamental design for a filter for swimming pool, substantially as shown.
